United States Patent Office

Des. 183,451
Patented Sept. 2, 1958

183,451

FORK OR SIMILAR ARTICLE

Irving Fiske, New Rochelle, N. Y., assignor to Welling Ware, Inc., New York, N. Y., a corporation of New York

Application February 25, 1958, Serial No. 49,790

Term of patent 14 years

(Cl. D54—12)

Fig. 1 is a plan view of a fork or similar article, showing my new design.

Fig. 2 is a side view thereof.

Fig. 3 is a bottom plan view thereof.

Fig. 4 is a cross-sectional view taken on line 4—4 of Fig. 1, as viewed in the direction of the arrows, drawn to an enlarged scale.

I claim:

The ornamental design for a fork or similar article, substantially as shown.
